Primary Examiner — Melanie Pellegrini

(57) **CLAIM**

The ornamental design for a finger ring as shown and described.

DESCRIPTION

1. Finger ring
- 1.1 : Perspective
- 1.2 : Front
- 1.3 : Back
- 1.4 : Top
- 1.5 : Bottom
- 1.6 : Right
- 1.7 : Left

The characteristic features of the design reside in the shapes as shown in the reproductions; the broken lines in the reproductions form no part of the claimed design.
